UNITED STATES PATENT OFFICE.

JOSEPH L. LYNCH, OF CHICAGO, ILLINOIS.

ATTACHING MEANS FOR BUTTONS AND BADGES.

1,045,160.

Specification of Letters Patent.

Patented Nov. 26, 1912.

Application filed November 27, 1911. Serial No. 662,651.

To all whom it may concern:

Be it known that I, JOSEPH L. LYNCH, a citizen of the United States, and a resident of the city of Chicago, in the county of 5 Cook and State of Illinois, have invented certain new and useful Improvements in Attaching Means for Buttons and Badges; and I do hereby declare that the following is a full, clear, and exact description of the same, 10 reference being had to the accompanying drawings, and the numbers of reference marked thereon, which form a part of this specification.

In many labor organizations, the various 15 unions require the members of the union each to obtain a monthly button or badge evidencing the continued good standing of the member in such union. Such buttons or badges are required to be worn or exhibited 20 during the month upon the clothing or cap of the member, and at the end of the month a new button or badge is issued and the old button thrown away or destroyed. This entails considerable waste, as the entire 25 structure is discarded. Sometimes also, picture or photograph buttons similarly constructed may be desired to be worn on particular occasions, and another at other times, and in consequence additional expense 30 in construction is incurred by affording independent attaching means for each device. Furthermore, the frequent attachment and detachment of such device to the clothing soon injures the garment, rendering 35 the same unsightly.

The object of this invention is to afford 40 an attaching device adapted for use in connection with a button top, to removably engage the same upon the clothing without the necessity of removing the attaching means or pin from the clothing and enabling any desired button top of a standard size, 45 to be immediately secured in place in lieu thereof, if desired.

It is also an object of the invention to afford an exceedingly strong and secure engagement of the button with the garment, preventing disengagement therefrom except 50 with intent.

The invention in its preferred form is illustrated in the drawings and more fully pointed out and defined in the appended claims.

In the drawings: Figure 1 is a top plan 55 view of a button embodying my invention. Fig. 2 is a bottom plan view thereof, show-

ing the attaching means in place. Fig. 3 is an enlarged fragmentary section. Fig. 4 is an inner face view of the attaching means showing the button top removed 60 therefrom. Fig. 5 is an edge view of the button. Fig. 6 is a similar view, taken at the opposite edge of the button. Fig. 7 is a section similar to Fig. 3, but illustrating a double locking means for engaging the 65 pin in closed relation.

As shown in the drawings: 1, indicates the button top constructed of pressed or stamped metal by means of a suitable die, and, as shown, circular in form, and with a 70 convex top portion, and secured thereto and covering the same is a sheet of celluloid or other suitable material 2, through which may be seen the picture, character or design secured beneath the same over the button 75 top. The integral peripheral flange of the top portion inclines inwardly toward its free edge, as shown in Figs. 1 and 7, and the free margin 3, thereof is rolled or turned over the celluloid covering rigidly binding 80 the same in place.

The attaching means comprises a metallic plate 4, pressed or stamped to a size to fit within the flange of the button and convex on its outer side, and provided with an upturned peripheral flange 5, which fits closely within said flange. Also pressed or stamped from said plate near the front edge thereof, is a downwardly struck hook 6, for engaging the pin and on each side thereof 85 adjacent said hook is an upwardly and outwardly inclined flange 7, which engages within the flange of the button top, as shown in Figs. 3 and 7. The pin 8, is bent at its inner end at a right angle with the body of 90 the pin, as indicated by 9, in Fig. 4, and the end 10, thereof is turned outwardly and inwardly through an aperture in said plate 4, and the pin engaged in place on said plate by means of an eye 11, provided therefor 95 integral with the plate 4, and at the opposite side thereof from the hook 6. The body of the pin is bent adjacent said eye wherein the pin is hinged so that when the pin is closed in the hook 6, as shown in Figs. 3 and 7, 100 105 the inner end 10, of the pin engages within the flange of the body top and oppositely from the flanges 7, on the plate.

The button top is secured in place by swinging the attaching plate at substantially a right angle with its pin, and inserting the rear end 10, of the pin and the 110

flanges 7, of the attaching plate within the flanges of the button top and then closing the pin and engaging the same upon its hook 6, whereupon said flanges 7, and the end of 5 the pin 10, lock the button top firmly in place. If desired, a portion of the flange of the button top may be turned downwardly and shaped to afford a hook 12, as shown in Fig. 7, together with a hook 6, engaged 10 by said pin and acting to secure the button or badge top from any rotational movement on the attaching means.

The operation is evident from the foregoing description. The attaching means 15 may, of course, be constructed of material of any desired or suitable quality or kind, as may also the button top, and the same may obviously be made for use in connection with articles of jewelry as well as for 20 the purposes hereinbefore described. When it is desired to detach the button, badge or article previously attached in place, the pin is merely released from its hook, permitting the attaching plate to swing outwardly with 25 reference to its pin, and the top portion to be lifted away therefrom. Another button top, badge or the like may be secured in place on the attaching plate without removing the pin from the clothing, and closed 30 and firmly engaged in place when the device is closed and the pin engaged upon its hook.

Of course, it is to be understood that details of the construction may be varied. I 35 have described but one (and that a preferred) form of my invention, and I therefore do not purpose limiting the patent to be granted on this application for patent otherwise than necessitated by the scope of the appended claims.

40 I claim as my invention:

1. Attaching means of the class described embracing a plate having a hook on one side thereof near its edge and one or more flanges adjacent thereto on the other side 45 thereof, and extending obliquely outward therefrom, a pin hinged at the other edge of the plate from the hook and adapted for engagement therewith, and a portion of said pin extending through the plate and oppositely from said flange or flanges, and adapted together with said flanges to engage within a hollow button top to connect the same firmly therewith.

2. Attaching means of the class described 50 embracing a plate having a hook on one

side thereof and flanges adjacent thereto on the other side thereof and extending outwardly therefrom, a pin hinged on the plate and adapted for engagement with said hook, and a portion of said pin extending through 60 the plate and oppositely from said flanges, and adapted together with said flanges to engage within a hollow button top to connect the same firmly therewith.

3. The combination with a button of the 65 class described, of an attaching plate adapted for engagement on one side of the button, a hook on the outer side of the attaching plate, outwardly and obliquely directed projections, a pin hinged on the attaching plate 70 oppositely from the hook and adapted for engagement therewith, the rear end of said pin extending through said attaching plate and acting as a lever to engage within the button oppositely from said projections 75 therein to afford an attachment for the attaching plate therein.

4. The combination with a button such as described of an attaching plate adapted to fill the rear side thereof, a hook on the outer 80 side the attaching plate near one edge, a projection adjacent the hook adapted to engage within the button, and a pin hinged on the plate opposite from the hook, the rear end of said pin extending through said attaching plate to lock the attaching plate in place 85 within the button when the pin is engaged upon its hook.

5. The combination with a button of the 90 class described of a circular attaching plate adapted for engagement on the rear side of the button, a hook at one edge of the attaching plate at the outer side thereof, inwardly and obliquely directed projections, one on each side of the hook, a pin hinged 95 on the attaching plate oppositely from the hook and adapted for engagement therewith, the rear end of said pin extending through the attaching plate and acting as a lever to engage within the button oppositely from 100 said projections therein to afford a three point attachment for the attaching plate therein.

In testimony whereof I have hereunto subscribed my name in the presence of two sub- 105 scribing witnesses.

JOSEPH L. LYNCH.
